HAT

Paul Jacobson, South Norwalk, Conn., assignor to
 The American Hat Company, Norwalk, Conn.,
 a corporation of Connecticut

Application December 20, 1934, Serial No. 758,513

1 Claim. (Cl. 2—181)

This invention relates to hats, and more particularly hats of the felt type and to a means for preventing discoloration of the felt of the hat by perspiration.

5 An object of this invention is to provide in a hat construction, means in the form of a novel band so constructed and disposed within the hat that the perspiration will not gradually work through the attaching means for the band and thereby discolor the hat adjacent the lower portion of the crown.

The particular object of the invention is to provide an inner hat sweatband in which the leather is attached to the reeding material without any visible stitching appearing on the face of the sweat band, whereby no stitching comes in contact with the brow or skin of the wearer.

Another object of this invention is to provide a novel sweat band construction which may be readily incorporated in various types of hats in addition to felt hats, which will not only prevent discoloration of the crown of the hat, but will also provide a construction which will not cause discomfort to the wearer of the hat such as is usually caused by the stitches for securing the band to the hat.

A further object of this invention is to provide in a sweat band construction means whereby a certain amount of yieldability is provided so that the hat will fit more snugly on the head of the wearer, and at the same time will not bind unduly.

With the foregoing and other objects in view, the invention will be more fully described hereinafter, and will be more particularly pointed out in the claim appended hereto.

In the drawing, wherein like symbols refer to like or corresponding parts throughout the several views,

40 Figure 1 is a fragmentary vertical section of a conventional hat construction having a sweat band constructed according to an embodiment of this invention mounted therein.

Figure 2 is a perspective view of the improved band.

Figure 3 is a fragmentary sectional view taken on the line 3—3 of Fig. 2.

Figure 4 is a sectional view taken on the line 4—4 of Fig. 2.

50 Figure 5 is a similar section of a commercial form.

Referring now to the drawing, 10 designates the crown of a conventional hat structure having a brim 11 extending outwardly of the crown. In hat constructions at present available it is the

practice to secure the sweat band to the hat at the juncture of the crown with the brim by a line of stitching extending through the band and exposed on the inner side of the band. This type of sweat band is objectionable in hats in that perspiration, oil or the like will soak up the threads forming the stitching and these liquids will follow the threads and thereby penetrate the crown of the hat and the inner portion of the brim in addition to the hat band disposed on the outside of the crown of the hat. The stitching also acts in the nature of a "file" annoying to the wearer.

5 In order, therefore, to provide a sweat band structure which will form a block or bar for moisture from the head of the wearer and do away with the annoying file feature, I have provided an inner band member 12 of suitable width and preferably formed of leather with the tanned or smooth surface innermost of the hat. This band member 12 has the lower edge thereof upwardly and outwardly turned as at 14 forming a rolled lower edge for the band 12. The upturned portion 14 is preferably initially disposed in outwardly spaced relation to the inner portion 15 of the band 12, thereby forming an expansion chamber 13. The words inner and outer are used in respect to the center of the hat.

A moisture-proof strip or band member 16 (well known) having its lower edge folded upwardly and outwardly as at 17 is secured to the upturned inner band portion 14 as by stitching 18. The band 16 has a looped or beaded portion 19 at the lower edge thereof, and in this looped or beaded portion 19 a stiffening member 20 is positioned. The stiffening member 20 is constructed in the form of an elongated strip of bamboo or reed, preferably round in transverse section so as to provide a round bead of relatively stiff construction extending below the lower edge of the crown 10. By turning up the moisture-proof band member 16 two layers of moisture-proof material are provided at the lower portion of the crown 10 of the hat, and due to the loop formed by turning up the lower edge 45 of the inner band 12 the outer band 16 will be normally spaced from the inner band 12.

The sweat band formed by the inner and outer bands 12 and 16 respectively may be secured to the hat, preferably by stitching engaging the hat 50 at the juncture 21 of the crown 10 with the brim 11. As will be noted from Figure 1 of the drawing, the bead 19 preferably extends below the juncture of the crown 10 with the brim 11 so that the body of the hat and the bead 19 and 55

the stitching will not contact with the head of the wearer.

It is well known that when leather is folded and then placed under pressure with possibly a 5 degree of heat the leather will retain its folded form. However, in the sweat band construction herein disclosed the lower end of the band 12 is not placed under sufficient pressure to dispose the upturned portion 14 in contacting relation 10 normally with the inner portion 15. In fact the upturned outer portion 14 is initially spaced away from the inner portion 15, thereby forming a loop or rolled portion at the bottom of the band 12 which is capable of yielding under pressure 15 of the head of the wearer. The lower rolled portion of the band 12, however, forms a wall or block to prevent perspiration or moisture from reaching the threads forming the stitching 18, so that this stitching 18 will not by capillary attraction 20 form a means whereby the crown 10 is discolored by such moisture.

After the leather band 12 with its upturned portion 14, has been secured to the beading in the manner described with the parts as in the 25 position shown in Figs. 1 to 4, (still unattached to the hat) they are put through a flanging machine which gives a bead to the lower portion of the band 16, somewhat as shown in Fig. 5, and this beading gives a further cushioning effect 30 and setting of the leather and disposes the beading 19 still further away from the head of the wearer.

This improved sweat band may be used on any of the present types of hat constructions, 35 including felts, straws, or other materials used in the construction of hats. It will be understood that the hat herein disclosed is only illustrative of the manner of applying the sweat band to a hat, and that other types or shapes of 40 hats may have the sweat band incorporated therein.

In Fig. 5 there is shown what is termed a commercial form of this band, that is, showing the band as it will appear when in actual use. As 45 here shown the lower end of the band 12 forms substantially a closed loop 22 inwardly of and slightly below the bead 19 so that at no time in the use of the hat will the head contact with the bead 19. It will be understood that during the 50 wearing of a hat the band is subjected to a slight strain in the pulling of the hat down on

the head, and this pull on the band will in a short time straighten out any loops or bends. However, with the construction herein disclosed the inner bead formed by the loop 22 will prevent disfiguration of the cushioning construction as 5 the hat is pulled down onto the head.

It will be noted that the bend of the leather forming the expansion chamber 13, is below the bead 19 as shown in Figure 1, and that it thereby prevents the head of the wearer to contact with 10 the bead, and at the same time the bent over band provides a soft or cushioning effect. The bead 19 as shown in Figure 1 is below the juncture of the brim and crown.

My improved device consists in having the 15 moisture-proof strip 16, which is bent upon itself and which encloses the reed 20, thus forming bead 19, superposed upon the inner part of the crown with the bead 19 extending below the juncture of the crown and brim and exterior to 20 the crown. The band member 12 has its marginal edge 14 superposed upon the strip 16 in a manner to permit the member 12 to extend below the bead, and said member 12 is then bent upon itself in spaced relation to its marginal portion, extending upwardly parallel with the crown 25 of the hat. Stitching 18 inserted close to the bead secures the band and strip to the crown.

It is obvious that various changes and modifications may be made in the details of construction and design of the above specifically described embodiment of this invention without departing from the spirit thereof, such changes and modifications being restricted only by the 30 scope of the following claim. 35

What is claimed is:—

In combination, a hat having a crown and a brim forming a juncture therebetween, with a sweatband construction comprising a moisture-proof strip bent upon itself and enclosing a reed, 40 forming a bead, said bead extending below the juncture of the crown and brim exterior of the crown, and a sweatband having one marginal edge portion superposed upon the strip, and stitching close to the bead securing said marginal 45 edge portion of said sweatband and the strip to the crown, said sweatband extending below the bead and being bent upon itself in spaced relation to said marginal portion, and extending upwardly parallel with the crown of the hat. 50

PAUL JACOBSON.
